UNITED STATES PATENT OFFICE.

KARL BAUMANN, OF URMSTON, ENGLAND, ASSIGNEE TO THE BRITISH WESTINGHOUSE ELECTRIC & MANUFACTURING COMPANY, LIMITED, OF LONDON, ENGLAND, A COMPANY OF GREAT BRITAIN.

CONDENSING STEAM-TURBINE PLANT.

1,246,039.

Specification of Letters Patent. Patented Nov. 13, 1917.

Application filed March 25, 1916. Serial No. 36,777.

To all whom it may concern:

Be it known that I, KARL BAUMANN, a citizen of the Confederation of Switzerland, and a resident of Urmston, in the county of 5 Lancaster, England, have invented a new and useful Improvement in Condensing Steam-Turbine Plants, of which the following is a specification.

This invention relates to plants for producing power, comprising a steam generator, a main steam turbine, a condenser, a feed water heater and their usual and appropriate auxiliaries, and with or without an economizer for conserving the heat of 10 the flue gases, and has for its object to provide an improved arrangement and construction of power plant of this kind whereby the overall efficiency is increased as compared with existing plants.

20 I attain this object, according to the present invention, by utilizing the steam which is used for packing the glands of the turbine, or the steam which leaks along the shaft into the glands, or the steam given off 25 from the water sealed glands, or the steam which leaks past the balance pistons, for heating the feed water, instead, as has heretofore been the practice, of exhausting said steam directly into the condenser or to an 30 intermediate point in the low pressure end of the turbine. Such packing, leakage, or heating steam is at a comparatively low pressure and the feed water heater in which it is utilized operates at a pressure below at- 35 mospheric.

In carrying the invention into effect several alternative arrangements are possible, for example:

A. The packing or leakage steam may be 40 used in an entirely independent heater of suitable construction.

B. The independent heater may be used in connection with another heater. In some cases the independent heater may be connected in series with the main feed water heater.

C. The packing or leakage steam may be used in a separate chamber, in the main feed water heater, formed by means of a 50 baffle plate or in any other suitable manner.

D. The packing or leakage steam may be mixed with heating steam taken from the main turbine or from some other source.

In most cases where two heaters are used

it is advisable first to heat the water by 55 means of steam taken from the main turbine and then to heat it to a higher temperature by means of the packing or leakage steam. Where packing or leakage steam at two different pressures is utilized the water 60 is preferably first heated by such steam at the lower pressure and then by such steam at the higher pressure.

In the case of water sealed glands the mechanical work expended on the sealing 65 water by the paddle wheel of the seal vaporizes a certain amount of water which appears as steam which enters the lantern space of the gland. This steam is led off and utilized for heating the feed water in 70 any one of the ways described above. In this way it will be readily perceived that the mechanical work expended on the water by the paddle wheel is largely recovered in the form of heat which is given up to the 75 feed water.

In operating arrangements of the above kind it sometimes happens that the extraction pump of the main condenser discharges its water intermittently, with the result that 80 the leakage steam, or the steam from the glands is not fully condensed in the feed water heater or heaters into which it is led. To obviate this a by-pass is provided for leading away to the main condenser or turbine exhaust, or any other suitable stage of the main turbine, any leakage steam or steam from the glands which may accumulate due to non-condensation in the heater. Said by-pass is provided with a back-pressure 85 valve or is otherwise so arranged as to prevent steam passing to the condenser, the turbine exhaust or an operative stage of the main turbine except when the pressure of the leakage steam or the steam from the 90 glands rises above a predetermined degree.

If desired said by-pass may take the form of a siphon tube containing water forming a seal which, in the event of the pressure of the packing or leakage steam rising above 10 a predetermined degree, will be blown out, permitting the steam to pass to an intermediate stage of the turbine or to the condenser or turbine exhaust. Suitable valves are preferably provided in the siphon tube 10 to enable the same to be refilled with water while the plant is in operation.

The accompanying drawings show dia-

grammatically by way of example several arrangements for carrying out the present invention. In the drawings Figure 1 is a view partly in section showing the feed water adapted to be heated with steam from the steam sealed glands of a turbine.

Fig. 2 is a view illustrating an arrangement of apparatus in which the feed water is heated by steam from a low pressure stage and also from the glands of the main turbine.

Fig. 3 is a view similar to Fig. 2, illustrating another arrangement.

In Fig. 1 the turbine 8 which, as illustrated, is of the impulse variety is connected to a condenser 9 in the usual manner. The condenser extraction pump is shown at 10 and the feed water heater at 11. The feed water after passing through the heater 11 is led away by the pipe 11^a to the economizer or to the hot well from which it is delivered to steam generator of the system. At either end of the turbine are steam glands 12, 13, the packing steam for which is supplied through the pipes 14, 15 to the lantern spaces 16, 17 respectively, of said glands. A pipe 18, connected with additional lantern spaces 19, 20 in the glands, leads the packing steam to the heater 11. Any steam which leaks along the shaft from the high pressure end of the turbine into the lantern space 20 will also be led away by the pipe 18 to the heater. A pipe containing a back pressure valve 22 connects the heater 11 to the main condenser 9. The function of said back pressure valve, as hereinbefore explained, is to prevent steam passing from the heater 11 to the condenser 9 except when the pressure of steam in the heater 11 rises above a predetermined degree, by reason of insufficient condensation therein.

Fig. 2 shows an arrangement similar to that shown in Fig. 1 except that the glands 12, 13 of the turbine are water sealed, the steam given off by such glands during operation being led away to the heater through the pipe 18 as in Fig. 1. The arrangement of Fig. 2 is shown as having a drain pipe 23 of small dimensions leading from the heater to the condenser 9, through which water and non-condensable gases accumulating in the heater may escape to the condenser.

The heater 11 is shown divided into two compartments by a division plate 25 located in the steam side of the heater and it constitutes a two-stage heater. In this arrangement the feed water is first heated by steam taken from an intermediate stage of the turbine and led into the heater through the pipe 26. The feed water is subsequently heated in the upper portion of the heater 11 by steam from the glands 12, 13 of the turbine conducted through the pipe 18 as described in connection with Fig. 1. The two

compartments of the heater 11 are interconnected by a pipe 27 containing an adjustable throttle or relief valve 28 constituting a bypass for non-condensable gases and a drain for condensed steam from the upper to the lower portion of the heater 11.

Pipe 18 is connected to pipe 26 by means of pipe 18^a and valve 22^a is interposed between pipe 18^a and pipe 26. This valve is constructed so as to permit the passage of steam from turbine glands 12 and 13 back into the low pressure section of the turbine provided more leakage steam is available than is needed for heating the feed water; the valve is constructed to prevent the passage of steam from the turbine to the glands.

Fig. 3 shows one arrangement which may be adopted in connection with a turbine of the reaction type having a plurality of balance pistons. In this case the feed water is first heated in the heater 11 by steam from the water packed gland 13 and by steam leaking past the last balance piston 34, such steam being led to the heater 11 through the pipe 18. A second heater 35 is connected in series with the heater 11 and is supplied through the pipe 36 with steam leaking past the balance piston 37. The heater 35 is connected by the pipe 38 with a point in the turbine 8 at which the pressure is approximately equal to that existing in front of the last balance piston 34. A non-return valve 39 is located in the pipe 38 to prevent steam from the operative part of the turbine flowing through the pipe 38 to the heater 35. A back pressure valve may also, if desired, be provided in the pipe 38 though this will, in many cases, be found unnecessary.

In the arrangement shown in Fig. 3, it will also be necessary to slightly raise the pressure behind the last balance piston 34, *i. e.*, to the left of the figure, and, if desired, make said piston slightly larger for the purpose of avoiding unbalanced end thrust, occasioned by the fact that it is desirable to increase the pressure of the steam delivered to the heater so that its temperature will be slightly above that to which it is desired to heat the water.

The arrangements herein described and illustrated have been given by way of example and not of limitation and the invention is not limited to the constructions shown and described. For example, where two feed water heaters, or their equivalent, are used they may be operated either in parallel or in series. The preferred arrangement, however, is that hereinbefore mentioned in which the heaters are operated in series, that is to say the feed water is first heated by steam at the lowest pressure, for instance by steam from a low pressure stage of the main turbine, and then by steam at a higher pressure, for example by steam

from the glands as described with reference to Fig. 2 of the drawings.

The invention herein set forth is not restricted to condensing steam turbine plants including an economizer or economizers utilizing the heat of the flue gases as it may equally well be applied to plants not provided with an economizer, such for example as condensing steam turbine plants installed 10 on marine vessels.

I am aware that the steam from the glands of back pressure turbines, which is at a comparatively high pressure, has been used for feed water heating and I do not broadly 15 claim this, the apparatus illustrated being adapted to employ steam below atmospheric pressure, and having novel structural features set forth in the appended claims.

Having now particularly described and 20 ascertained the nature of my said invention and in what manner the same is to be performed, I declare that what I claim is:

1. In combination with a steam turbine, feed water heating means operating below 25 atmospheric pressure, means for delivering leakage steam from the turbine to said heating means and means for discharging non-condensable gases from said heating means.

2. In combination with a steam turbine, 30 having packing glands, feed water heating means operating below atmospheric pressure, means for delivering leakage steam from the turbine to said heating means and valved means for delivering steam from said 35 heating means to a region of pressure lower than that of said heating means.

3. In combination with a steam turbine having packing glands containing steam, feed water heating means operating below 40 atmospheric pressure, means for delivering leakage steam from the turbine to said heating means and means employing a non-return valve for delivering steam from said heating means to a low pressure working 45 stage of the turbine.

4. In combination with a steam turbine, a multi-stage feed water heating means op-

erating below atmospheric pressure, means for delivering leakage steam from the turbine to one stage thereof, means for delivering steam from a working stage of the turbine to another stage thereof and means for discharging non-condensable gases therefrom. 50

5. In combination with a turbine, packing glands for the turbine rotor containing steam, feed water heating means adapted to operate below atmospheric pressure, a condenser, a connection between said heating means and said condenser and means for delivering steam from said glands to said heating means. 55

6. In combination with a turbine, feed water heating means operating below atmospheric pressure, means for delivering leakage steam from the turbine to said heating means, a condenser and means connecting said heating means to said condenser. 60

7. In combination with a steam turbine, a condenser connected to the exhaust thereof, feed water heating means operating below atmospheric pressure, connections including an extraction pump between said condenser and said heating means, means for delivering leakage steam from the turbine to said heating means and a drain from 70 said heating means to said condenser. 75

8. In combination with a steam turbine, feed water heating means operating below atmospheric pressure, a condenser for said turbine, means including an extraction pump connecting said condenser and said feed water heating means, a drain from said heating means to said condenser, a non-return valve in said drain and means for delivering 80 leakage steam from the turbine to the said feed water heating means. 85

In testimony whereof, I have hereunto subscribed my name this third day of March, 1916.

KARL BAUMANN.
